US00D971249S

(12) **United States Design Patent** (10) Patent No.: **US D971,249 S**
Chen et al. (45) Date of Patent: **** Nov. 29, 2022**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Kevin Will Chen**, Cupertino, CA (US);
Alan C. Dye, San Francisco, CA (US);
Christopher Wilson, San Francisco,
CA (US); **Eric Lance Wilson**, San
Jose, CA (US)

(73) Assignee: **Apple Inc.**, Cupertino, CA (US)

(**) Term: **15 Years**

(21) Appl. No.: **29/825,295**

(22) Filed: **Jan. 31, 2022**

Related U.S. Application Data

(63) Continuation of application No. 29/769,870, filed on
Feb. 8, 2021, now Pat. No. Des. 942,475, which is a

(57) **CLAIM**

The ornamental design for a display screen or portion
thereof with graphical user interface, as shown and
described.

DESCRIPTION

The FIGURE is a front view of a display screen or portion
thereof with graphical user interface showing the claimed
design.

The outermost broken lines in the FIGURE show a display
screen or portion thereof, and form no part of the claimed
design. The other broken lines in the FIGURE show portions
of the graphical user interface that form no part of the
claimed design.

1 Claim, 1 Drawing Sheet
